UNITED STATES PATENT OFFICE.

ROBERT M. CARSON AND JOHN J. LEAHY, OF PHILADELPHIA, PENNSYLVANIA.

FABRIC.

Application filed November 28, 1921. Serial No. 518,189.

To all whom it may concern:

Be it known that we, ROBERT M. CARSON and JOHN J. LEAHY, citizens of the United States, residing at Philadelphia, in the county of Philadelphia and State of Pennsylvania, have invented new and useful Improvements in Fabrics, of which the following is a specification.

This invention relates to woven fabrics, and, more particularly, to fabrics intended primarily for use in carpets, rugs and the like; and this application is a continuation in part of our abandoned application Serial No. 489,752, filed August 4, 1921, for a patent upon a fabric.

An object of the invention is to provide a two ply fabric, having a stiffening back or base of inferior material and a ribbed pile-like face which may be plain or figured by means of a figuring weft.

It is an object of the invention to provide such a fabric which may be produced by means of a combination of weft picks, binder threads, binder picks, stuffer warp, jacquard machine lifts and specially cut out cards or cams. In other words, it is an object of the invention to produce this fabric upon an ordinary loom such as is employed for the production of the "two face" reversible type of carpet or rug known as "art squares".

It has long been a desire of carpet manufacturers to produce upon this type of loom a single face two-ply fabric having a stiff back, such as a Brussels carpet, and a face having a pile or rib resembling in appearance, the face of the Brussels carpet.

The present invention contemplates the provision of such a fabric, its production upon an ordinary loom, the obtainance of the ribbed or pile face effect and the figuring by the special combination of binder threads, stuffers and weft picks hereinafter set forth.

The accompanying drawings illustrate diagrammatically the interweaving of the threads in a piece of fabric embodying the invention.

In the drawings:

Fig. 1 is a face view of a portion of the 50 fabric.

Fig. 2 is a back view.

Fig. 3 is a cross section taken parallel to the warp threads, showing the fabric before the lay of the loom has come up. 55

Fig. 4 is a view similar to Fig. 3 showing the completed fabric.

Referring to the drawings for a more detailed description, the back of the fabric comprises stuffer warp threads 10 arranged in basal groups of a plurality of threads, the groups being spaced apart; in the illustrated embodiment of the invention there are four threads in each group, although the number may be varied as desired. The 60 back also comprises weft threads 11 which are placed beneath the warp and may be formed of inferior material, in the illustrated embodiment the stuffer threads being jute and the weft paper. 70

The fabric face is of ribbed pile-like construction, having an appearance somewhat resembling the face of a Brussels carpet. It comprises a weft arranged in groups of three threads each, the several groups being 75 divided off in Figure 3 by vertical dotted lines. In the illustrated embodiment of the invention each group consists of a non-figuring fine thread 12 and two woolen shots 13; one woolen shot may be brown and the 80 other green, indicated by the letters B and G, respectively. Placed between the fabric back and the face weft are stuffer ends 14, one end being located above each set of the back stuffer warp threads. Referring more 85

particularly to Figure 4, which shows the relative position of the threads in the completed fabric, it will be noted that the intermediate stuffer ends are substantially straight and superposed above the concealed 90 woolen face shots, which, in the illustrated embodiment of the invention, are indicated as green. It will be understood, of course, that in parts of the fabric the position of the brown and green shots will be reversed 95 to form a different design which is done by

operating the stuffer ends by a jacquard machine and specially cut cards or cams.

The back and face of the fabric are bound together by means of binder warps 15, 16, 6 positioned between the sets of back stuffer warps, as indicated clearly in Figure 2. The binder 15 passes over the brown and green woolen face shots, then through the fabric under the back weft thread 11, and 10 subsequently to the face of the fabric to pass over the succeeding brown and green shots. The binder 16 passes under the brown and green weft threads, crosses the binder 15 between the green shot and the 15 adjacent fine shot 12, and over the fine shot and subsequently disappears into the fabric beneath the succeeding brown and green shots. It will be noted that the binders which are of any fine thread, such as 20 worsted, are non-figuring and assist in forming the rib upon the face of the fabric. These binders divide the face weft threads by first locking together two woolen shots, and then securing a fine face shot with the 25 back weft thread 11, there being three face weft shots to one basal weft shot in each group. In the completed fabric, shown in Figure 4, it will be noted that the back stuffer ends 10 and the intermediate stuffers 30 14 are held securely in the fabric by means of the binders, and in creating the design the stuffer ends 14 are woven with the woolen face shots so that the individual members of the pairs of woolen shots are 35 superposed, one above the other, in Figure 4, the green shots being shown as concealed.

Referring more particularly to Figure 3, if the green shots are to be concealed to produce a solid brown effect, the green shots 40 are passed under the stuffer ends 14, as indicated in Figure 3, and when the lay of the loom comes up the brown shots on each side are brought together, each green shot being thus placed beneath an adjacent 45 brown shot. In Figure 3, the position of the threads are shown before the lay of the loom comes up in order clearly to indicate the path of the various threads. It will be understood, of course, that it may be desirable at times to conceal the brown shots to 50 produce a solid green effect, and at such times, the brown threads pass under the stuffer ends 14, as do the green in Fig. 3.

It will be understood that the particular 55 colors designated in the illustrated fabric, as well as the materials specified for use, may be varied. However, we have found that it is particularly desirable to employ woolen threads for the face weft, since the 60 stuffer ends 14 and the binders cooperate with them to produce a ribbed effect, as distinguished from the plain smooth face of most fabrics heretofore obtained by weaves ordinarily produced upon the general type 65 of loom. To illustrate the extent to which

the materials may be varied we have produced fabrics of this weave in which the face weft shots are of chenille and produce the figured effects. It is intended through the specification and claims, when the term 70 "woolen shots" is employed, to cover such variations in the use of materials as would naturally occur to one skilled in the art and familiar with the particular weave as disclosed in this application. It will be observed at this point, however, that when such materials as chenille are employed the ribbed effect is not so noticeable. The stuffer ends 14 may be of jute or paper; it is not necessary that any more expensive 80 material be employed, since these ends do not appear upon the face of the fabric, but are at all times concealed between the face and the back of the fabric. It should be borne in mind that even when the ends are 85 positioned above any of the woolen face picks the weave is such that the adjacent woolen threads are positioned over that portion of the stuffer end and the portion of the woolen shot which it conceals. 90

It has not been thought necessary to give a detailed description of the successive changes in the operation of the loom involved in the production of a fabric such as that described herein. The mechanism must 95 be such as to operate the warp threads in the way described to produce the fabric desired, and suitable forms of such mechanism may readily be devised by an understanding of the fabric itself. It should be 100 borne in mind, however, that the stuffer ends 14 are preferably operated by a jacquard mechanism and specially cut cards or cams. The binders and the backing stuffer warp are heddle lifts. 105

The fabric produced has a relatively stiff back of inferior material and a ribbed woolen face with pattern and figuring effects, according to the operation of the stuffer 14 by the jacquard mechanism. So 110 far as we are aware, we are the first to produce upon an ordinary loom a single faced fabric having this ribbed or pile face with a stiffening back of inferior material and to produce such a fabric with figure or pattern 115 effects.

What we claim is:—

1. A fabric of the class described comprising a stiffening base of relatively inferior material; and a ribbed pile-like face 120 comprising relatively large weft threads substantially in contact, relatively fine weft threads positioned between the adjacent first mentioned weft threads, and binder warps binding together said face and base. 125

2. A fabric of the class described comprising a stiffening base of relatively inferior material; and a ribbed pile-like face comprising relatively large weft threads, relatively fine weft threads positioned be- 130

- between the adjacent first mentioned weft threads, warp stuffer threads between said base and the face weft, said stuffer threads being interwoven with the face weft threads 5 for pile-like pattern effects, and relatively small binder warps binding together said base and face.
3. A fabric of the class described comprising a stiffening base of relatively inferior material; and a ribbed pile-like face comprising relatively large weft threads substantially in contact, relatively fine weft threads positioned between the adjacent first mentioned weft threads, stuffer warp threads 10 between said face and base, said stuffer threads at times passing over certain relatively large weft threads to produce pattern effects, and plain relatively small binder warps binding together said face and base.
- 15 4. A fabric of the class described having a stiffening base of relatively inferior material comprising straight longitudinal stuffer threads arranged in groups of two or more and a weft beneath the stuffer threads; 20 and a patterned ribbed pile-like face comprising weft threads and plain binder warps binding together said base and face.
- 25 5. A fabric of the class described having a stiffening base of relatively inferior material comprising straight longitudinal stuffer threads arranged in basal groups of two or more and a weft beneath the stuffer threads; and a ribbed pile-like face comprising figuring weft threads, longitudinal 30 stuffer threads between said base stuffer threads and said face weft threads, said longitudinal stuffer threads being interwoven with the face weft threads for pile-like pattern effects, and plain binder warps 35 binding together said base and face.
- 40 6. A fabric of the class described having a stiffening base of relatively inferior material comprising straight longitudinal stuffer threads arranged in spaced basal groups of two or more, and a weft beneath the stuffer threads; and a ribbed pile-like face comprising figuring weft threads and pairs 45 of plain binder warps between said groups of stuffer threads binding together said base and face, said binder threads binding together alternately a pair of face weft threads, one of which is concealed, and then a single face weft thread with a base weft thread.
- 50 55 7. A fabric of the class described having a stiffening base of relatively inferior material comprising straight longitudinal stuffer threads arranged in spaced basal groups of two or more, and a weft beneath the stuffer threads; and a ribbed face comprising colored weft threads and pairs of plain binder warp threads between said 60 groups of stuffer threads binding together said base and face, there being three face weft shots to a single basal weft shot, said 65 binder warp threads crossing between the second and third face weft shots, one binder warp thread then extending over the third face weft shot and the other binder warp thread under the base weft thread, the 70 binder warp threads then recrossing and extending one over and the other under the succeeding pair of face weft shots.
- 75 8. A fabric as specified in claim 6 having longitudinal stuffer threads between said base stuffer threads and said face weft, said face weft threads at times passing under certain of said last mentioned stuffer threads to be concealed and thereby to produce pattern effects.
- 80 9. A fabric as specified in claim 7 having longitudinal stuffer threads between said base stuffer threads and said face weft, said face weft threads at times passing under certain of said last mentioned stuffer threads to be concealed and thereby to produce pattern effects.
- 85 10. A fabric of the class described having a stiffening base structure of relatively inferior material; and a patterned ribbed pile-like face structure comprising relatively large figuring weft threads arranged in pairs, the individual threads of the pairs being superposed, relatively small weft threads between the adjacent pairs of said 90 first mentioned weft threads, and plain relatively small binder warps binding together said base and face.
- 95 11. A fabric of the class described having a stiffening base structure of relatively inferior material; and a ribbed pile-like face structure comprising relatively large weft threads arranged in pairs, the individual threads of the pairs being superposed, relatively fine weft threads arranged between the 100 adjacent pairs of the first mentioned weft threads, stuffer warp threads between said base and face, said stuffer threads at times passing over and concealing members of said pairs of weft threads to produce pattern effects, and relatively fine binder warps binding together said face and base.
- 105 12. A fabric of the class described having a stiffening base of inferior material comprising jute stuffer warp threads and paper 110 weft threads, a ribbed pile-like face comprising figuring woolen weft threads, and binder warps binding together said base and face.
- 115 13. A fabric of the class described having a stiffening base of inferior material comprising stuffer warp threads and weft threads, a ribbed pile-like face comprising figuring woolen weft threads, plain stuffer warp ends between said back and face, and 120 at all times concealed therebetween, said face weft shots at times passing under said intermediate stuffer ends to be concealed, the adjacent weft shots being positioned over and concealing the superposed stuffer end,
- 125 130

and plain binder warps binding together said base and face.

14. A fabric of the class described having a stiffening base of inferior material, such as paper or jute, comprising stuffer warp threads and weft threads, a ribbed pile-like face comprising weft threads arranged in groups of three shots, each group comprising a small plain worsted thread shot and two figuring thread shots, and binder warps binding together the face and base.

15. A fabric of the class described having a stiffening base of inferior material, such as paper or jute, comprising stuffer warp threads and weft threads, a ribbed pile-like face comprising weft threads arranged in groups of three shots, each group comprising a small plain worsted thread shot and two figuring thread shots, and binder warps binding together the face and base, said binder warps being arranged in pairs binding together in each group of face picks, two woollen shots and the fine shot, with the back weft shot.

16. A fabric, as specified in claim 14, having longitudinal stuffer ends between said base and the face weft, said face shots at times passing under said stuffer ends to be concealed and thereby to produce pattern effects.

17. A fabric, as specified in claim 15, hav-

ing longitudinal stuffer ends between said base and the face weft shots, said face shots at times passing under said stuffer ends to be concealed and thereby to produce pattern effects.

18. A fabric of the class described, having a stiffening base of inferior material comprising straight longitudinal warp stuffer threads and weft shots beneath said warp; and a patterned pile-like face comprising figuring woollen weft threads arranged in pairs, certain of the individual members of the pairs being concealed by being placed beneath the other member of the pair to produce the pattern effects, and binder warps binding together said base and face.

19. A fabric of the class described, having a stiffening base of inferior material comprising straight longitudinal warp stuffer threads and weft shots beneath said warp; and a patterned face comprising figuring woollen weft threads arranged in pairs, certain of the individual members of the pairs being concealed by being placed beneath the other member of the pair to produce the pattern effects, and non figuring binder warps binding together said base and face.

In testimony whereof we have hereunto set our hands.

ROBERT M. CARSON.
JOHN J. LEAHY.
